INVENTOR -

Morris E. Thompson

BY *Richard Oliver.*

ATTORNEY

UNITED STATES PATENT OFFICE.

MORRIS E. THOMPSON, OF ARLINGTON, IOWA.

DISK-HARROW BOXING.

1,287,518.

Specification of Letters Patent. Patented Dec. 10, 1918.

Application filed September 24, 1917. Serial No. 192,956.

To all whom it may concern:

Be it known that I, MORRIS E. THOMPSON, a citizen of the United States, residing at Arlington, in the county of Fayette and 5 State of Iowa, have invented certain new and useful Improvements in Disk-Harrow Boxings, of which the following is a specification.

My invention relates to improvements in 10 boxings and bearings and is especially adapted to be used in connection with disk harrows.

An important object of my invention is to provide a device of the above mentioned 15 character which is dust and dirt proof and keeps the spindle thoroughly lubricated.

Another object of the invention is to provide a device of the above mentioned character including means whereby the disks 20 may be removed and the boxing passed over the ends of the spindle.

A further object of my invention is to provide a device of the above mentioned character which is simple in construction, 25 strong, durable and efficient in practice.

Other objects and advantages of the invention will be apparent during the course of the following description.

In the accompanying drawings forming a 30 part of the description, and wherein like numerals are employed to designate like parts throughout the same,

Figure 1, is a vertical sectional view of the 35 device in position on the axle of a disk harrow, and

Fig. 2, is a vertical section of the same taken on line 2--2.

In the drawings, wherein for the purpose of illustration is shown a preferred embodiment of my invention, the numeral 3 designates one end of a square shaft or axle which rotates with the spindle 4. This spindle is provided with an enlargement 5 which when positioned in the boxing prevents any lateral or longitudinal movement of the same. Beveled washers 6, arranged upon the ends of the spindle and mounted upon the axle are adapted to engage the opposite faces of the disks 7. One of each pair 45 of washers has one face adjacent the disk, beveled concave, while the other, or coacting washer, has its face adjacent the opposite side of the disk, convex. This arrangement affords a secure clamping means for mounting the disks upon the axle or shaft 50 55 3. It will be noted that these washers are

formed separate from the spindle, thereby making it possible to pass the sections of boxing over the ends of the spindle. The spindle 4 is adapted to rotate within the stationary boxing, which consists of two sections 8 and 9. These sections are normally secured together by means of the bolts 10, or any suitable means. The section 8, adjacent its coacting section 9, is provided with a recess to receive the enlarged portion 5 of the spindle. The outer ends of the boxing are adapted to snugly fit the spindle, and are oppositely externally threaded to receive apertured packing caps 11. A lubricating means, such as waste saturated with an oil, is positioned between the ends of the threaded portions of the boxing and the packing caps. An oil duct 12 in the section 9 has communication with the spindle 75 proper, while the oil duct 13 has its terminal upon the enlargement 5 of the spindle.

This boxing or bearing may be suspended from the harrow frame by any suitable means, and it will be seen that this boxing 80 being stationary, and the disks rolling along the ground, will rotate the axle and spindle within this bearing. In order to remove the boxing, the nut and washer positioned on the end of the axle are moved and the disk and beveled washers passed over the end of the axle. The nuts and bolts 10 are then removed from the boxing, and the section comprising one half the boxing passed over the end of the axle. 85

It is to be understood that the form of my invention herewith shown and described is to be taken as a preferred example of the same, and that various changes in the shape, size and arrangement of the parts 95 may be resorted to without departing from the spirit of the invention or the scope of the subjoined claims.

Having thus described my invention, I claim:

1. A boxing comprising a stationary housing consisting of a pair of sections, one of said sections being provided with a recess adjacent the bore therethrough, and a spindle rotatably mounted in said housing, said spindle being provided with an enlargement 105 adapted to be received in the recess in said section.

2. A boxing comprising a housing consisting of a pair of sections, each section having a bore therethrough, a spindle rotatably mounted in said housing, means for locking 110

the sections together, and means in said housing for lubricating said spindle.

3. A boxing comprising a housing consisting of a pair of sections having a bore therethrough, one of said sections having its face adjacent the co-acting section provided with a recess communicating with the bore therethrough, a spindle rotatably mounted in said housing, said spindle being 10 provided with an annular flange to be received in said recess.

4. A boxing comprising a housing having a bore therethrough, said bore having an enlarged part intermediate its end, a spindle 15 rotatably mounted in said housing, said spindle being provided with an annular flange adapted to be received in the enlarged part of said bore, said housing being provided with a pair of oil ducts one of which com-

municates with the enlarged part of the 20 bore, and the other being adapted to communicate with the bore through the housing.

5. In combination with a housing consisting of a pair of sections each having a bore therethrough, a spindle rotatably mounted 25 therein, a square shaft passing through said spindle, a pair of detachable washers mounted upon said shaft at the extremities of said spindle, narrow disks interposed between said washers, and means for detachably securing said washers upon said shaft. 30

In testimony whereof I affix my signature in presence of two witnesses.

MORRIS E. THOMPSON.
